US00D383727S

United States Patent [19]

Caruso et al.

[11] Patent Number: **Des. 383,727**[45] Date of Patent: ****Sep. 16, 1997**[54] **PROTECTIVE ELECTRICAL OUTLET PLUG**

[75] Inventors: **James F. Caruso**, Evanston; **Craig S. Scherer**, Wilmette; **Michael C. Thuma**, Desplaines, all of Ill.

[73] Assignee: **BRK Brands, Inc.**, Aurora, Ill.

[**] Term: **14 Years**

[21] Appl. No.: **54,712**

[22] Filed: **May 20, 1996**

[51] LOC (6) Cl. **13-03**

[52] U.S. Cl. **D13/156**

[58] Field of Search **D13/154, 156; 174/66, 67; 220/242; 439/135, 136, 148, 149**

[57] **CLAIM**

The ornamental design for a protective electrical outlet plug, as shown.

DESCRIPTION

FIG. 1 is a front perspective view of a protective electrical outlet plug embodying the principles of the present invention;

FIG. 2 is a rear perspective view of the protective electrical outlet plug of FIG. 1;

FIG. 3 is a top view of the protective electrical outlet plug of FIG. 1;

FIG. 4 is a front view of the protective electrical outlet plug of FIG. 1;

FIG. 5 is a side view of the protective electrical outlet plug of FIG. 1 as viewed from the left hand side of FIG. 1;

FIG. 6 is a side view of the protective electrical outlet plug as viewed from the right hand side of FIG. 1;

FIG. 7 is a bottom view of the protective electrical outlet plug of FIG. 1; and,

FIG. 8 is a rear view of the protective electrical outlet plug of FIG. 1.
